WATER COOLER

Byron E. Freitag, River Edge, and Frederick Burggraf, Jr., Livingston, N. J., assignors to General Electric Company, a corporation of New York

Application September 3, 1953, Serial No. 26,688

Term of patent 14 years

(Cl. D67—4)

To all whom it may concern:

Be it known, that we, Byron E. Freitag and Frederick Burggraf, Jr., citizens of the United States of America, residing at River Edge, New Jersey, and Livingston, New Jersey, respectively, have invented a new, original, and ornamental Design for a Water Cooler, of which the following is a specification, reference being had to the accompanying drawing, forming a part thereof, in which:

Fig. 1 is a perspective view, slightly reduced, of a water cooler embodying our new design;

Fig. 2 is a front view of the water cooler of Fig. 1;

Fig. 3 is a side view of the water cooler of Fig. 1; and

Fig. 4 is an enlarged fragmentary perspective view of a few of the elements forming the front pattern portion of our new design.

The bottle shown in dotted lines in Fig. 1 has been omitted in Figs. 2 and 3 for convenience of illustration as the essential features of our design reside in the portions shown in full lines in each of the figures. It is to be understood that while only one side of the water cooler is illustrated, the opposite side is substantially like the side shown.

We claim:

The ornamental design for a water cooler, as shown and described.
